UNITED STATES PATENT OFFICE.

LOUIS KÁLMÁNOVITS, OF NEW YORK, N. Y.

BILLIARD-CUE.

No. 927,150.

Specification of Letters Patent.

Patented July 6, 1909.

Application filed February 14, 1908. Serial No. 415,810.

To all whom it may concern:

Be it known that I, LOUIS KÁLMÁNOVITS, a subject of the King of Hungary, and a resident of the city of New York, borough of Manhattan, in the county and State of New York, have invented a new and Improved Billiard-Cue, of which the following is a full, clear, and exact description.

This invention relates to billiard cues, and more particularly to billiard cues having removable tips, means for securely and removably mounting the tips in position, and, if so desired, between the tip and the cue, a body of resilient material, which increases the effect of the blow when the cue strikes the ball.

An object of the invention is to provide a simple, strong and durable billiard cue which is inexpensive to manufacture, and which obviates the necessity for gluing or otherwise securing a tip thereto.

A further object of the invention is to provide a billiard cue having the tip removably mounted thereupon so that if the tip becomes accidentally disengaged it can be replaced without the aid of glue or other adhesive.

A still further object of the invention is to provide a billiard cue having a resilient shive or disk intermediate the cue end and the tip, whereby the normal resiliency of the tip is increased and the force exerted upon a ball when the latter is struck by the cue is augmented.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a perspective view showing the end of a billiard cue and a tip removed from the cue, my invention being applied thereto; Fig. 2 is a partial longitudinal section of the end of the billiard cue, having an embodiment of my invention applied thereto, showing the removable tip and the means for mounting the same in position; Fig. 3 is a transverse section on the line 3—3 of Fig. 2; Fig. 4 is a similar view on the line 4—4 of Fig. 2 and Fig. 5 is an enlarged end view showing a stud carried by the billiard cue and serving to engage a socket carried by the tip to mount the tip in position.

Before proceeding to a more detailed explanation of my invention, it should be understood that I provide means for removably attaching a cue tip to a billiard cue, thereby obviating the necessity for gluing or otherwise securing the tip in position at the cue end, as this operation is one which involves considerable difficulty and labor, and places the cue out of operation for a more or less protracted period. It frequently happens, that a tip, because of a misstroke or some other accident, is broken loose from the cue. With my invention it is merely necessary to replace the same tip by suitably engaging the socket of the same with a stud mounted at the end of the cue, or by replacing the detached tip with another similar one. The operation of replacing the tip can be performed in a few moments, and when the tip is in position it is so firmly secured at the cue end that it requires the exertion of considerable force to remove it accidentally or otherwise.

I provide a resilient shive or disk consisting preferably, of rubber or the like, which is interposed between the tip and the cue end, thereby increasing the resiliency of the former, which usually consists of leather or some similar material. If this extra resiliency is not desired, the rubber shive or disk can be replaced by one of leather, pressed paper or the like. I have found it of advantage to increase the resiliency of the tip in this way, as it augments the force of impact of the cue against the ball, and also permits the execution of certain strokes with greater ease and success.

Referring more particularly to the drawings, I provide a cue body 10 which may be of any preferred or common form, and may be fashioned from any suitable material, or, as is usually the case, of wood. At the smaller or tip end of the cue is fashioned a substantially circular recess 11 in which is mounted a flat disk 12 of steel or other suitable material, and secured in position by means of screws 24 or in any other desired manner. The outer surface of the disk 12 is flush with the face of the cue end. The disk 105 has a substantially central opening therethrough formed to receive the shank 13 of a catch member or stud 14. The shank 13 is preferably of tapered form and is embedded in the wood or other material of the cue. The stud 14 is preferably of spring form, having transverse notches 15 which

permit the compression of the stud to enter the socket, as will appear more clearly hereinafter. The stud has a rigid collar 16^a which seats against the outer face of the disk 12. A shive or disk 16 of rubber or other resilient material is mounted at the cue end and encompasses the stud, having a substantially central opening 26 for this purpose.

10 The tip 17 in its flat face has a circular recess 18 in which is mounted a socket plate 19. The latter is secured in position in any suitable manner, for example, by gluing, and may be fashioned from metal or any other material adapted for the purpose. The socket plate 19 carries a socket 20 presenting a recess and formed to receive the stud 14 and having an inwardly disposed rim 21, which is received by a groove 22 of the stud 14 when the latter is driven home into the socket. It will be understood that the stud sections are resiliently compressed when being inserted in the socket, to pass the rim 21 and to permit the engagement of the latter 25 with the groove 22. The tip 17 may be of any suitable form and may have the usual leather or pressed paper disk 23. The latter has an opening to receive the socket, while the tip itself has a depression into which the bottom of the socket extends. The socket plate opening with the depression, forms a recess in which the socket is mounted upon the tip. The socket 20 preferably has spurs 30 which pass through suitable openings of 35 the plate 19, and are bent over to hold the socket upon the plate.

Having thus described my invention, I claim as new and desire to secure by Letters Patent:

40 1. In combination, a billiard cue having at the end a projecting stud, a tip having a recess, a socket in said recess and projecting therefrom, said socket being formed to receive and removably hold said stud, and a 45 resilient disk between said cue and said tip.

2. In combination, a billiard cue having

at the end a projecting stud, a tip having a recess, a socket in said recess and projecting partly therefrom, said socket being formed to receive and removably hold said stud, and 50 a disk between said cue and said tip and having an opening receiving said projecting part of said socket.

3. In combination, a billiard cue having at the end a projecting spring stud, a tip 55 having a recess, a socket in said recess and projecting partly therefrom, said socket having an inwardly disposed rim forming a constricted opening, said socket being adapted to receive and removably hold said spring 60 stud, and a disk between said cue and said tip and having an opening receiving said projecting part of said socket.

4. In combination, a billiard cue and a tip, 65 said cue having at the end a stud, said tip having a recess, a disk having an opening, a shive of resilient material and having an opening, said recess and said openings of said shive and said disk registering, and a socket in said recess and said openings, and 70 having a constricted rim, said socket being formed to receive and removably hold said stud.

5. In combination, a billiard cue and a tip, 75 said cue having at the end a plate provided with an opening, and a spring stud having a shank extending through said opening and embedded in said cue, said tip having a recess, a disk over said recess and having an opening, and a socket in said recess and having a constricted rim beyond said opening of said disk, said socket being adapted to receive said stud when the latter is forced inwardly beyond said rim to hold said tip removably in position.

85 In testimony whereof I have signed my name to this specification in the presence of two subscribing witnesses.

LOUIS KÁLMÁNOVITS.
